UNITED STATES PATENT OFFICE

MICHAEL R. O'KEEFE, OF TACOMA, WASHINGTON

COLLAPSIBLE TUBE CLOSURE

Application filed July 17, 1931. Serial No. 551,499.

This invention relates to an improved closure and fastener therefor which is expressly devised and suitable to serve as an efficient closure for collapsible tubes of the type now generally used for containing and dispensing toothpaste, shaving cream and analogous pharmaceutical preparations.

It is a matter of common knowledge that the ordinary closure used on tubes of this kind is a screw cap. This is susceptible of easy displacement and subject to frequent loss. I am aware of the fact however that retaining devices have been provided to overcome this disadvantage to some extent, for which reason I do not claim to have discovered a closure which is a revelation from a standpoint of practical usage. Instead, I have involved and produced an improved and refined structure which, I believe, better fulfills the requirement of tube closures of this general classification.

It follows that the principal purpose and feature of the invention is the particular selection of appropriate parts suitably and mechanically combined to serve as an economical, efficient and dependable closing means for the discharge neck of a collapsible tube.

In the drawing:

Figure 1 is a side elevational view of a tube equipped with the invention.

Figure 2 is a side view thereof.

Figure 3 is an enlarged detail section on the line 3—3 of Figure 1.

Figure 4 is a horizontal section.

Figures 5 and 6 are plan views of details.

In the drawing, observing Figure 3 in conjunction with the other views, it will be seen that the tube is generally represented by the numeral 7 and comprises the usual collapsible body portion 8 and the conical top 9 having an ejector neck 10. The neck is here shown as formed with an intermediate flange 11 while the terminal thereof is slightly tapered to accommodate the telescopically fitting cap 12.

Attached to this neck is a wire mounting which is here formed from a single length of wire coiled as at 13 around the neck and beneath the flange 11. It is thus confined between the apex portion of the top 9 and

flange 11. The terminals of this wire are formed into spring coiled sockets 14 which receive the inturned trunnions 15 formed on the ends of the arms of the wire actuating lever 16. The wire is bent to provide a suitable finger grip 17 and the intermediate portions of the arms are convolved as at 18 to form coupling eyes.

The inturned ends 19 on the U-shaped bail 20 fit into these eyes and the bent portions 21 of the bight of the bail, is rockably connected with the crown 22 of the cap. Thus, the operating lever 16 is pivotally and flexibly attached to the sockets 14 which are in turn fastened to the neck and the ends of the arms of the bail 20 are pivotally attached to the eyes 18 and swingably are fastened to the crown portion of the cap 12. In this way a novel operating and clamping as well as cap retaining device is provided.

In practice the cap is simply slipped down over the mouth of the neck as seen in Figure 3 and the finger portion 17 of the lever 16 is pressed downwardly which reacts to draw the bail 20 downwardly and to thereby clamp the cap tightly in closed position. The springs 14 provide sufficient flexibility to allow the terminal ends of the arms of the bail to pass beyond dead center as shown in the canted position represented in side elevation in Figure 2.

Accordingly the lever is maintained closed and the cap drawn tightly down on the neck as is obvious. This structure, therefore, serves as a novel cap mounting, retaining and fastening device.

It is thought that the description taken in connection with the drawing will enable a clear understanding of the invention to be had. Therefore, a more lengthy description is thought unnecessary.

While the preferred embodiment of the invention has been shown and described, it is to be understood that minor changes in shape, size, materials and arrangement of parts coming within the field of invention claimed may be resorted to if desired.

I claim:

1. In a structure of the class described, in combination, a collapsible tube embodying

a discharge neck, a cap adapted to fit slidably and telescopically on said neck, a bail swingably attached to the crown portion of the cap, an operating lever pivotally attached to the bail and means for connecting said lever swingably with said neck.

2. In a structure of the class described, in combination, a collapsible tube embodying a discharge neck, a cap adapted to fit slidably and telescopically on said neck, a bail swingably attached to the crown portion of the cap, an operating lever pivotally attached to the bail and means for connecting said lever swingably with said neck, said means embodying resilient sockets to provide for the relative adjustment between the bail and lever to maintain the parts assembled and in either open or closed position.

3. In a structure of the class described, in combination, a collapsible tube including an ejector neck having an intermediate flange, a mounting comprising a length of wire coiled around the neck beneath the flange and formed with terminal spring coiled sockets, a U-shaped lever having the free ends of its arms inturned to provide trunnions, said trunnions being rockably mounted in said sockets, a cap fitting telescopically on said neck, a bail attached to said cap, and means operatively connecting the bail and lever.

4. In a structure of the class described, in combination, a flexible dispensing tube including a discharge neck having a confining flange intermediate its ends, an attaching device comprising a length of wire coiled around said neck beneath said flange and formed with terminal spring coiled sockets, a substantially U-shaped operating lever having a finger piece, having its arms formed with inturned trunnions rockably mounted in said sockets, and having their intermediate portions of its arms convolved into coupling eyes, a cap fitted on said neck, a bail having its bight portion rockably attached to the crown portion of the cap, the arms of said bail being inturned and fitted into said eyes.

In testimony whereof I affix my signature.
MICHAEL R. O'KEEFE.
